UNITED STATES PATENT OFFICE.

LAWRENCE A. BURCH, OF JAMESTOWN, NEW YORK.

RATCHET ATTACHMENT FOR TOOLS.

Application filed December 7, 1922. Serial No. 605,458.

To all whom it may concern:

Be it known that I, LAWRENCE A. BURCH, a citizen of the United States, residing at Jamestown, in the county of Chautauqua and State of New York, have invented certain new and useful Improvements in Ratchet Attachments for Tools, of which the following is a specification.

The present invention relates primarily to improvements in ratchet attachments for tools of various types by means of which partial rotation may be made effective in impelling the working implement where full turns may not be obtained.

The main object in view is the provision of a simple unitary device which is capable of application to tools at any point between the lever and the bit or other instruments for doing the work. In this connection it will be understood that the tool as a whole may vary in form so that the specific embodiment which is hereinafter disclosed is merely illustrative of the adaptation of the attachment, reference being more particularly made to a companion application for my improvements in combination tools, filed December 7, 1922, Serial Number 605,457, for further exemplifications of its utility.

Reference will now be had to the accompanying drawing in which:

Figure 1 is a side elevation of a brace form of operating tool to which my ratchet attachment is applied;

Fig. 2 is a side elevation of the ratchet attachment alone; and

Figs. 3 and 4 are sectional views on the lines 3—3 and 4—4, respectively, of Fig. 2.

Corresponding and like parts are referred to in the following description and indicated in all of the views of the drawing, by like reference characters.

The device which forms the subject matter of this invention is in the nature of a small unitary article having relatively few parts but capable of application to tools for the purpose of obtaining a ratchet movement of the working implement in forward or reverse directions, as the case may be. The attachment comprises a body member 1, having a longitudinal bore therethrough which forms at one end a socket 2 into which the male extremity of the operating tool, such as shown in Figure 1 of the drawing, may be inserted. At the opposite end of the bore is arranged a stub shaft 3 having fixed thereto a collar 4 formed on its

inner end with annular teeth 5, therefore constituting a ratchet wheel. The shaft and wheel are retained within the body by the bushing 6 snugly fitting within the enlarged portion of the bore opposite the end of the socket 2.

The body 1 is provided with a lateral opening 7 communicating with the bore and in this opening is pivotally secured a pawl 8 formed at one end with a finger-piece 9 by means of which the pawl may be rocked about its pivot 10. The pawl is provided with a pair of spaced teeth 11, arranged so as to lie at opposite sides of the pivot 10, these teeth being engageable with the ratchet wheel to hold the same against movement in one direction or the other, depending upon which of the teeth is in interlocking engagement.

To hold the pawl in its coacting relation to the ratchet wheel I apply to the body a yieldable pressure producing member or spring 12 detachably secured by a screw 13 so as to extend over the lateral opening 7. The free extremity of this spring is bent into substantially V-shape form as indicated at 14 so as to coat with one side or the other of a projection 15 on the pawl 8. The body is preferably provided with oil openings 16 extending therethrough for suitably lubricating the ratchet wheel.

In the operation of the device the shank of the operating tool is slipped into the socket 2 of the body and the pawl 8 is positioned so as to engage one or the other of the teeth 11 with the ratchet wheel, depending upon whether forward or reverse movement is to be imparted to the stub shaft 3. Preferably this shaft is formed with a spring-pressed ball 16 for maintaining engagement with the working tool or implement after the manner shown in the companion application above referred to. In other words, the shaft may be slipped into a detachable socket of proper size when it is desired to screw nuts upon bolts or remove them from the same. Or by proper coupling means the shaft may be connected to another type of working device such as a drilling bit or a screw driver, after the manner well known in this art.

In Fig. 1 I have shown as one form of operating device a brace-like implement comprising the shank sections 17, 18 connected by a detachable grip-piece 19, a detachable head 20 being applied to one end

of the implement so as to facilitate the operation of the device. These shank elements are detachable or interchangeable and enable the tool as a whole to be changed in form 5 or the elements thereof arranged in a compact manner for shipping purposes or the like. The features of the implement, however, form the subject matter of the application above referred to and, therefore, are 10 not specifically claimed herein.

Having thus described my invention, what I claim as new and desire to secure by Letters Patent, is:

As an article of manufacture, a ratchet attachment for tools comprising a body recessed at one side with a peripheral slot communicating with said recess and having a socket at the opposite side for a tool con-

nection, a collar projected beyond the body and having a tool-engaging shank at one end 20 and a ratchet head at the opposite end seated in the recess of the body with an intermediate elongated bearing surface extended from said body, a bearing sleeve disposed in said body to project therefrom and surround said bearing surface, a reversible pawl transversely pivoted within the peripheral slot in the body and having opposite teeth to engage said ratchet head, and a spring disposed concentric to the outer face of the 25 body and bearing upon a projection on said pawl intermediate of its teeth to retain it in either position.

In testimony whereof I affix my signature.

LAWRENCE A. BURCH.
